UNITED STATES PATENT OFFICE.

FRED A. ABRAHAM, OF MARTINSVILLE, INDIANA.

CONVERTIBLE BABY SEAT.

Application filed July 13, 1926. Serial No. 122,182.

The object of this invention is to provide a simple structure which is convertible into either a high-chair especially for use at a table, or a nursery-chair, or a swing, as occasion may demand, the construction being inexpensive and strong and such that the seat may be folded into an exceedingly compact condition for convenience in handling, packing and transportation, as more fully 10 hereinafter set forth.

This application is a continuation in part of my co-pending application Serial No. 11,289, filed February 24, 1925.

In the drawing—
15 Fig. 1 is a perspective view of the seat adjusted for use as a high-chair;

Fig. 2 is a similar view of the seat adjusted for use as a nursery-seat;

20 Fig. 3 is a similar view of the seat adjusted for use as a swing;

Figs. 4, 5, 6 and 7 are detail views herein-after more particularly described.

Referring to the drawings annexed by reference-characters, 10 designates the central or main frame which consists of a heavy, 25 stiff wire bent into rectangular form. This rectangular wire-frame has stretched across it the nursery-seat fabric 11, this fabric being connected to the four frame-bars by 30 hems 12.

A back-frame fabric 16 is attached to the rear bar of the seat-frame through the medium of a stiff, rectangular wire-frame 17 whose vertical side rods are pivotally connected to said rear bar of the seat-frame by means of eyes 18 formed on the lower end of said vertical rods. The fabric is attached to the back-frame by suitable hems 16' formed in the edges of the substantially 40 rectangular piece of fabric used for this purpose. The eyes 18 enable the back member to be folded down flat over the seat member.

Another frame consisting of a rectangular 45 piece of fabric 19 hemmed to a rectangular wire-frame 20 is pivotally connected to the front bar of the seat-frame by eyes 21. This stiff front frame is adapted to be swung over upon the seat-frame and reinforce the same 50 when the appliance is used as a chair or a swing, as shown in Figs. 1 and 3. When the appliance is to be used as a nursery-seat, this front panel or frame is swung over forwardly and allowed to hang freely. 55 When the appliance is used on a chair of the

proportions shown in Fig. 2, this depending front frame will serve as a leg-rest and as a guard. For the purpose of hanging the appliance in proper position for use as a high-chair or as a nursery-seat, I provide the 60 back frame with a pair of hooks 22 which are pivotally connected to the top bar of the back-frame so as to adapt them to be hung over the top bar of a dinner chair, as shown in Figs. 1 and 2. When thus hung over the back of a chair, the seat will be suspended at a desirable distance above the seat of the chair, as illustrated.

Fabric suspension tape-members 23 are employed to serve as side-guards and also to hold the seat-member in proper relation to the back-member. These suspension tapes or members connect the two upper corners of the back-frame to the two front corners of the seat-frame; for convenience in connecting these tapes to their respective frames, I form the side-bars of the two frames into eyes 24. For the purpose of holding the child in the seat, I provide a body-band 25 which is attached to the fabric of the back-frame and extends around in front of the suspension members 23 so as to pass under the arms of the baby. For the purpose of disconnecting this body-band 25, I sever it at one point and provide one end with a series of button-holes 26 and the other end with a button 27. The two parts of this body-band are respectively stitched to the side guard tapes 23. To keep the child from slipping out forwardly off the front edge of the seat, I provide a central strap 28 which is slidably attached to the body-band 25 at its upper end (by means of a loop formed on the upper end of said strap 28) and detachably attached to the front edge of the seat-frame by means of a button arrangement 29. This central strap 28 is positioned to lie between the legs of the baby and therefore will, together with the body-strap 25 and the suspension members 23, hold the child safely in the seat, preventing it wriggling off the seat in any direction.

When not in use, it will be seen that the three panels or frames may be readily folded over on each other to make a very compact article. The straps 23, 25 and 28 are of flexible fabric and may be disposed of in any suitable way; for instance, they may be folded between the frame members.

When the appliance is used as a swing, as shown in Fig. 3, the chair-hooks 22 are out of use and instead four suspending tapes 30 are used, each one of these being provided with a snap-hook 31 at its lower end for detachable attachment to the suspension loops 24. The tapes at their upper ends may be supplied with similar snap-hooks or other means (not shown) for suspending them from an overhead structure. These suspending members 30 are desirably made of fabric similar to the other fabric members, so that they may be readily placed between the frame-members in packing or 15 placed in the container in which the folded appliance is enclosed. To keep the seat, when thus used as a swing-seat, from tilting forwardly, I tie the front tapes 30 to the top of the back-frame by means of rigid 20 brace-rods 32 which are each desirably covered with a rubber tube. These brace-rods are held removably in place by having their rear ends bent laterally at 33 so as to be insertable in the top hem 16' of the 25 back-frame, and their forward ends are provided respectively with a downward bend 34 adapted for insertion in a fabric tube 35 formed in the front tapes 30 by folding over the tape and stitching it. This construction enables these brace-rods to be 30 readily placed in position and removed therefrom, and, when in position, they effectively hold up the front edge of the seat and thus prevent the child from being 35 tilted into an uncomfortable position.

The front edge of the fabric 19 is provided with an extension-flap 36 which, when this fabric 19 lies over the main seat, folds down over the front bars of the main seat 40 and thus forms a finish or valance along the open side of the wire frame 19 and thus nicely disposes of the raw edge of the fabric that would otherwise be presented by the 45 front edge of the seat. This flap 36 is formed by providing the edge of the fabric with a wide hem.

It will be observed that a feature of importance is the stiff frame 20 covered by the taut fabric 19 and pivotally mounted on the 50 front bar of the seat-frame. This stiff frame, as will be observed, is a little narrower than the seat-frame, so that it may be readily swung over upon the top surface of the fabric of the seat-frame and 55 will lie closely thereagainst. By making this frame 20-19 in this manner, it is unnecessary to provide fastening devices for clamping it down on the seat-frame, while at the same time this swinging frame serves

to provide a substantial closed seat in connection with the nursery-seat 11.

A further feature of importance is the provision of a closed eye 24 at each of the upper corners of the back-frame and a similar eye at each of the front corners of the 65 seat-frame, whereby these eyes may be utilized as connections for the guard suspension-straps 23 and also for the swing-straps 30, these latter being detachably connected to the eyes by means of snap-hooks 31. In 70 this way, I provide a simple construction for readily converting the folding chair into a swing.

In all the figures except Fig. 6, the front eyes 24 are shown as lying in a horizontal 75 position, projecting laterally from the seat-frame; this is the best arrangement of these eyes, as they are thereby gotten out of the way of the child and at the same time give the widest possible distance between the two 80 straps 23. These eyes, however, may be arranged in vertical position, as shown in Fig. 6, without departing from my invention.

It will be seen by an inspection of Fig. 4 that, when the stiff seat-frame 19-20 is folded over upon the main seat, its wire frame lies within the wire frame of the seat proper, thereby conducing materially to compactness when the device is folded up 90 for packing or transmission.

What I claim as new is:

1. A baby-seat and swing embodying a seat-member and a back-member hinged together, flexible suspension-members attached respectively to the upper corners of the back-frame and the front corners of the seat-frame, and removable brace-rods pivotally and detachably connected at their rear ends to the top of the back-frame, the axis of the pivots being horizontal and at their forward ends to the front suspension-members.

2. A baby-seat and swing embodying a seat-member and a back-member hinged together, flexible suspension-members attached respectively to the upper corners of the back-frame and the front corners of the seat-frame, and removable brace-rods connected at their rear ends to the top of the back-frame and at their forward ends to the front suspension-members, said brace-rods being provided with bent ends adapted at the rear to enter a hem at the top of the back-frame and at their forward ends to enter tubes in the front suspension-members.

In testimony whereof I hereunto affix my signature.

FRED A. ABRAHAM.
